FOOTWEAR WASHING APPARATUS

Abraham Y. Schultz, Harry Schultz, Solomon Schultz, and Marvin Saks, University City, Mo.

Application September 20, 1951, Serial No. 247,452

2 Claims. (Cl. 134—71)

1

This invention relates to washing apparatus and methods, and more particularly to apparatus for and methods of washing articles in a continuous process.

The invention is herein described as it relates to an apparatus for and a method of washing footwear, i. e., boots or shoes, with a mold-proofing or fungi-proofing liquid, but it will be understood that the principles of the invention may be applicable to apparatus for and methods of washing other articles in other liquids for other purposes, as, for example, in the laundering of clothing and the dry cleaning of garments, or in impregnating operations.

The invention, as it pertains to the washing of footwear, is particularly concerned with the treatment of military combat boots or shoes with a liquid mold-proofing or fungi-proofing composition, such as para-nitrophenol, or the like.

Among the several objects of the invention may be noted the provision of an apparatus for and method of washing articles in a continuous process at low cost, with flexibility of control of the treatment; the provision of an apparatus and a method particularly for washing hollow articles open at one end, and more particularly for washing footwear such as boots or shoes; the provision of an apparatus and a method of the class described which provides for draining and at least partially drying articles upon emergence from the wash liquid; and the provision of an apparatus of the class described which is of economical construction and reliable in operation and a method of the class described which requires a minimum of manual operations and no special skill. Other features will be in part apparent and in part pointed out hereinafter.

The invention accordingly comprises the elements and combinations of elements, steps and sequence of steps, features of construction and manipulation, and arrangements of parts which will be exemplified in the structures and methods hereinafter described, and the scope of the application of which will be indicated in the following claims.

In the accompanying drawings, in which one of various possible embodiments of the invention is illustrated,

Fig. 1 is a side elevation of an apparatus constructed in accordance with the invention;

Fig. 2 is an enlarged vertical transverse section taken on line 2—2 of Fig. 1;

Fig. 3 is an enlarged vertical transverse section taken on line 3—3 of Fig. 1;

Fig. 4 is an enlarged vertical transverse section taken on line 4—4 of Fig. 1;

2

Fig. 5 is a vertical longitudinal section taken at one end of the apparatus on line 5—5 of Fig. 2; and

Fig. 6 is a vertical longitudinal section taken at the other end of the apparatus.

Similar reference characters indicate corresponding parts throughout the several views of the drawings.

Referring to the drawings, which illustrate the invention as applied to apparatus for washing footwear, i. e., boots or shoes, in a mold-proofing or fungi-proofing liquid, such as an emulsion of para-nitrophenol, the apparatus is shown to comprise an elongate sheet metal tank 1 having a bottom 3, vertical sides 5 and vertical ends 7 and 9. In practice, the tank is of the order of eighty feet long, three feet wide and three feet high, for example. It is positioned within an outer shell 11 with studs 13 between the sides 5 of the tank and the shell. The tank and shell are mounted on transverse beams 15 which rest on longitudinal rails 17. Gusset plates 19 stiffen the sides of the shell. The studs 13 support longitudinal beams 21. The sides 5 of the tank have flanges 23 at their upper edges overlying these beams. The sides of the shell are higher than the sides of the tank. Transverse beams 25 span the sides of the shell, resting on the flanges 23 of the tank. The shell is stiffened at its upper edge by angle iron stiffeners 27 and braced by angle iron cross-braces 28.

An endless chain conveyor generally designated 29 extends the length of the tank from near its end 7 to near its other end 9. This conveyor comprises a pair of endless chains 31 arranged side-by-side in parallel vertical planes on opposite sides of the central vertical longitudinal plane of the tank. The chains are trained around upper and lower sheaves 33 and 35 near the end 7 of the tank and around upper and lower sheaves 37 and 39 near the end 9 of the tank so that the conveyor has a lower horizontal reach 41 travelable from near the end 7 to near the end 9 within the tank, and an upper horizontal reach 43 directly above the lower reach travelable in the opposite direction above the tank.

The upper sheaves 33 near the end 7 of the tank are fixed on an upper transverse shaft 45 journaled in bearings 47 mounted on the sides of the shell 11. These bearings are adjustable longitudinally for tensioning the chains. At 49 is shown a platform mounted on posts 51 which extend upward from the sides of the shell. On the platform is a motor 53 coupled to drive the input shaft of a speed changer 55 through a belt and pulley drive 56, the output shaft of the speed

changer being coupled to drive the shaft 45 through a chain and sprocket drive 57. The lower sheaves 35 are mounted on short transverse idler shafts 59 carried by brackets 61 in the tank 1. The upper sheaves 37 near the end 9 of the tank are mounted on short transverse idler shafts 63 carried by brackets 64, and the lower sheaves 39 are mounted on short idler shafts 65 carried by brackets 67 in the tank 1. Shafts 45 and 63 are in the same horizontal plane above the tank, and shafts 59 and 65 are in the same horizontal plane below the top of the tank. The conveyor is driven counterclockwise as viewed in Figs. 1, 5 and 6, i. e., its lower reach travels from end 7 to end 9 of the tank, and its upper reach travels back in the opposite direction above the tank.

The upper reaches of the chains 31 are guided in upwardly opening horizontal channels 69 extending longitudinally above the tank from near the upper sheaves 33 to near the upper sheaves 37. These channels are mounted on the upper ends of vertical supports 71 which are fixed to the cross-braces 28. The sides of each channel have inwardly directed flanges 73 so that the opening of the channel is a slot-like opening narrower than the channel, being slightly wider than the thickness of the links of the chain. The lower reaches of the chains are guided in downwardly opening horizontal channels 75 extending longitudinally within the tank from near the lower sheaves 35 to near the lower sheaves 39. The channels 75 are fixed to the lower ends of the supports 71. The sides of each channel 75 have inwardly directed flanges 73 like the channels 69. Every other link of each chain is guided vertically in the slot-like opening of its respective channel, the remaining links riding horizontally within the respective channel.

The conveyor 29 is equipped with a series of supports on both sides thereof for holding footwear to be carried through a dip in the tank in such a way that the entire surface of any article of footwear is out of contact with any other article or parts of the apparatus for complete exposure for treatment and elimination of abrasion. More particularly, each support comprises a lateral bar 77 secured to two laterally aligned vertical links of the two chains 31 and projecting on opposite sides of the conveyor. The projecting portions of each bar form legs which are bent as indicated at 79 so that those legs on the upper reach of the conveyor incline upward and those on the lower reach incline downward. On the outer ends of each bar are rods 81 having rings 83 at their ends, these rods forming feet at the ends of the legs for receiving a boot or shoe. Each rod or foot 81 is so inclined relative to the vertical plane of the conveyor that those feet on the upper reach of the conveyor incline upward toward this plane, and those feet on the lower reach incline downward toward this plane. Within the tank, the feet 81 travel closely adjacent the sides of the tank, so that the sides serve to prevent footwear from falling off into the tank.

The tank 1 has a cover 85, supported on beams 25, which extends from near the end 7 to near the end 9, leaving space at the ends where the conveyor enters and emerges from the tank. A drying hood 87 is provided on the tank enclosing a part of the upper reach of the conveyor extending from near the end 9 of the tank (where the conveyor emerges from the tank) to a point well short of the end 7 of the tank. This leaves a considerable accessible portion of the

upper reach of the conveyor between the posts 51 and the exit end of the drying hood so that workers standing at unloading stations on opposite sides of the tank may place shoes on and remove shoes from the supports on this portion of the conveyor. The hood is of arched form, with a tapering chamber 89 at its exit end, and forms with the cover 85 a drying tunnel. A fan 91 in an opening in the exit end wall 93 of the chamber 89 blows air over steam coils 95 in the chamber and causes a flow of heated air through the tunnel in the direction counter to that of travel of the upper reach of the conveyor. The cover 85 keeps the air from evaporating liquid in the tank.

At 97 is shown a pipe for filling the tank with the treating liquid. Steam pipes 99 extend the length of the tank for heating the liquid. At the end 9 of the tank, a motor-driven pump 101 is mounted on a support 103. An inlet pipe 105 extends from within a filter-screened space 107 in the tank to the inlet of the pump. The outlet of the pump is connected by a pipe 109 to pipes 111 which extend the full length of the bottom 25 of the tank 1 and a pipe 112 which extends the length of the tank just under the center of the bars 77 in the lower reach of the conveyor. Pipes 111 have outlets 113 at spaced intervals. Pipe 112 has laterally directed outlets 114 at spaced 30 intervals. Part of the flow from pipe 109 is delivered through a pipe 115 to a filter 117, filtered liquid being delivered from the filter to the tank by a pipe 119. At 121 is shown an emergency overflow outlet connected by a pipe 123 to a 35 drain.

In operation, the tank 1 is filled with the treating liquid. The pump is driven continuously to withdraw liquid from the tank and return it to the tank via pipes 111 and 112 and filter 40 117. The liquid returned to the tank through pipes 111 is discharged through outlets 113 continuously to agitate the liquid in the tank. The liquid returned to the tank through pipe 112 is 45 discharged through outlets 114 to agitate the liquid in footwear travelling through the tank. The conveyor 29 is continuously driven at a relatively slow rate of speed. The fan 91 is operated to blow heated air through the drying tunnel.

Workers stationed on opposite sides of the tank 50 1 adjacent its end 7 apply footwear (combat boots as shown in Figs. 2 and 3) to the feet 81 and legs 79 on the upper reach of the conveyor as it approaches the upper sheaves 33. The boots are positioned heel down on the feet, and their open 55 tops are down. As the boots travel around and down into the tank at the end 7 of the tank, they are inverted to open-top-up position so that they readily fill with the liquid in the tank. Then they travel immersed in the liquid throughout the 60 length of the lower reach of the conveyor, and become impregnated with the liquid. The agitation of the liquid insures thorough washing action on both the outside and the inside of the boots. As the boots travel around and up out 65 of the tank at the end 9 of the tank, they are returned to their heel and top down position, and all excess liquid therein drains out and back into the tank. The impregnated boots then travel through the drying tunnel wherein they are at 70 least partially dried by the flow of hot air. As the boots emerge from the drying tunnel, they are removed by workers stationed on opposite sides of the tank 1 rearward of the loading station as regards the direction of travel of the 75 upper reach of the conveyor. This clears the

boot supports for application of more boots there-to by the workers at the loading station.

The length of time that the boots are immersed in the treating liquid may be varied by varying the speed of the conveyor. It will be understood, however, that the conveyor will not be driven so fast as to make it impractical for workers to apply and remove the boots.

In view of the above, it will be seen that the several objects of the invention are achieved and other advantageous results attained.

As many changes could be made in the above constructions and methods without departing from the scope of the invention, it is intended that all matter contained in the above description or shown in the accompanying drawings shall be interpreted as illustrative and not in a limiting sense.

We claim:

1. Apparatus for washing footwear comprising an elongate tank having a bottom, vertical sides and ends, an endless chain conveyor extending the length of the tank and having a horizontal lower reach travelable in one direction within the tank from near one end of the tank to near its other end and an upper reach travelable in the opposite direction above the tank, said conveyor comprising a pair of endless chains arranged in parallel vertical planes and having a series of lateral bars projecting on opposite sides of the conveyor and having feet at their outer ends for holding footwear, each bar being secured to the outer side of two laterally aligned links of the respective chains, the feet on the lower reach of the conveyor being travelable closely adjacent the vertical sides of the tank so that footwear is prevented from falling off into the tank, the tank having a cover extending from near one end to the other, a drying hood on the tank enclosing

the upper reach of the conveyor and extending from near said other end of the tank to a point short of said one end of the tank, the hood and part of the cover forming a drying tunnel, and means for causing a flow of heated air through the tunnel in the direction counter to that of travel of the upper reach of the conveyor.

2. Apparatus as set forth in claim 1 wherein the bars and feet are formed to hold footwear open end up as it travels through the tank and open end down as it travels above the tank.
